UNITED STATES PATENT OFFICE.

ROMAINE R. HARRIS, OF SAN DIEGO, CALIFORNIA, ASSIGNOR OF ONE-TWENTIETH TO JENNIE B. WICKIZER, ONE-TWENTIETH TO C. F. HOLLAND, ONE-TWENTIETH TO TILLA BELCHNER, SIX-TWENTIETHS TO MAUDE F. GALIGHER, AND ONE ONE-HUNDREDTH TO WILHELMINE C. GRIFFIN, OF ALAMEDA, CALIFORNIA.

ARTIFICIAL LIMB.

Application filed March 7, 1921. Serial No. 450,203.

To all whom it may concern:

Be it known that I, ROMAINE R. HARRIS, a citizen of the United States, residing at San Diego, in the county of San Diego and 5 State of California, have invented certain new and useful Improvements in Artificial Limbs, of which the following is a specification.

This invention relates to artificial limbs 10 and particularly to certain improvements in artificial arms.

It is the object of the invention to provide an artificial arm which includes various parts generally corresponding to the parts 15 of the natural arm, and which also includes means for moving such parts to various positions and locking the same, and further means for releasing the locked parts when desired, the construction, as a whole, being 20 so arranged and connected that it will be capable of performing to a large extent the motions and functions of the natural arm. The invention is particularly intended for the use of persons who have lost all, or practically all of an arm, the construction being 25 such that the motions and operations of the various parts can be carried out by suitable movements of the stump of the arm, or shoulder in various directions. With the 30 foregoing and other useful objects in view, the invention is embodied in the construction described in the following specification, embraced in the appended claims, and illustrated in the accompanying drawings, in 35 which:

Figure 1 is a perspective view of my improved arm shown applied to the body of a person;

Figure 2 is an enlarged front elevation of 40 the upper portion of my improved construction;

Figure 3 is a detailed front view showing particularly the construction of the hand section of the arm;

45 Figure 4 is an enlarged detailed view showing the construction of one of the jointed members forming the fingers of the hand;

Figure 5 is a side view of the upper portion 50 of the arm and the cage;

Figure 6 is a detailed view, showing the relation between the fingers and thumb members of the hand;

Figure 7 is a longitudinal sectional view, partly in elevation, showing certain features 55 of the upper arm section and certain features of the lower arm section;

Figure 8 is a transverse sectional view on the line 8—8 of Figure 7;

Figure 9 is a detailed transverse sectional 60 view on the line 9—9 of Figure 1, showing the construction of certain parts of the upper arm section;

Figure 10 is a detailed view showing the arrangement of certain guides employed for 65 guiding the cables used in operating the movable parts of the arm;

Figure 11 is a detailed sectional view on the line 11 of Figure 5, showing the means employed for locking the upper arm section 70 against swinging movement;

Figure 12 is a vertical elevation showing further details of the mechanism illustrated in Figure 11; and

Figure 13 is a diagrammatic view, illustrating the manner of connecting and moving the cables for operating the various movable parts of the arm.

Referring to the drawings in detail, the numeral 10 represents what is termed the 80 cage section of the arm, this section being shaped to fit over the shoulder of a person to whom the arm is applied. The numeral 11 represents the upper arm section, 12 the lower arm section, and 13 the hand section, 85 all of these sections being supported from the cage 10.

The cage 10 includes a curved member 14, which is adapted to lie upon the shoulder of a person and extend from the front to the 90 rear thereof. A second curved section 15, is rigidly secured at right angles to the member 14, the member 15 being arranged to extend from the front to the rear of the shoulder of a person, and to lie beneath the 95 shoulder. Suitable braces 16 are secured between the members 14 and 15 to hold the same in rigid relation. A curved member 17 is also secured to the member 15, such member 17 being also arranged to extend 100 over the shoulder of a person from the front to the rear thereof. A laterally extending top member 18 is secured to the members 14 and 17, this top member being curved downwardly at its outer end and provided with 105 spaced portions 18^a, 18^b, between which the

upper arm section 11 is pivoted, as later described. A number of operating paddles or levers 19 are pivotally secured to various parts of the cage 10, these paddles or levers being so positioned as to be operated by movements of the shoulder or stump of the arm. These paddles constitute the means by which the various movable parts of the arm are operated, such operation being effected through the medium of various cables C, hereinafter termed primary cables, connected to the paddles 19 and extending through suitable guides and rollers generally designated 19^a, on the cage and then to the various parts to be moved.

The upper arm section 11 is pivoted between the downwardly extending portions 18^a of the cage, as heretofore noted, and such pivotal section is secured through the medium of a ring 20, pivotally supported on opposite sides to the parts 18^a of the member 18.

The main portion of the upper arm section 11 is formed of two substantial parallel bars 25 or members 21, 21, which are pivotally secured to said ring 20 on an axis substantially at right angles to the pivotal axis of the pivot between the ring 20 and the parts 18^a. The pivotal connection between the bars 21 and the ring 20 is such that the upper arm section may swing freely, relative to the ring 20 when certain locking mechanism is not operative. This locking mechanism is illustrated in Figures 11 and 12 of the drawing, in which 20^a represents one of the pivot members secured to one of the bars 21 and upon which the upper arm section swings, this pivot member being arranged in an opening in the ring 20 and being circular in cross section, except that one face thereto is flattened, as shown at 20^b. A locking block 20^c is hingedly supported adjacent the pivot member 20^a and is provided with a flat face adapted to engage the flat portion 20^b of the pivot member whereby rotation of said member is prevented. This locking block 20^c is so arranged that it can be moved about its hinge connection to withdraw the flat face thereof from contact with the flat face 20^b of the pivot member 20^a. When the block 20^c is thus withdrawn the upper arm section 11 is free to swing relative to the ring 20. One of the primary cables C is secured to the pivot block 20^c, which cable passes through suitable guides and rollers and is attached to one of the paddles or levers 19 heretofore described, this paddle or lever being operated whenever it is desired to withdraw the pivot block 20^c and permit the arm to swing.

Below its upper end, the upper arm section carries a series of levers 25 which are pivotally secured within a ring 26 rigidly secured between the bars 21, 21 of the upper

arm section. The levers 25 are preferably mounted upon a common pivot 27 mounted on spaced bars 27^a rigidly secured to the ring 26, and each of said levers at its free end is provided with a laterally extending projection or arm 28 each of which carries a series of teeth 29. Adjacent the end of each of said levers 25 there is arranged a pivotal dog 30 these dogs being preferably arranged on a single pivot rod 31 mounted in the bars 27^a, and each being provided with a lug 32 adapted to engage with the teeth 29 of the corresponding lever 25. Each of the dogs 30 is yieldingly held against the end of the corresponding lever 25 by means of a spring 33 and suitable mechanism is provided for simultaneously withdrawing said dogs from engagement with the levers 25. Such mechanism comprises two bars 34 which are pivoted upon the pivot rod 31 heretofore mentioned, and which extend upwardly and are connected by means of a cross bar 35 which bar is adapted to contact simultaneously with the dogs 30. A secondary cable C' is attached to the bar 35, this cable passing around a roller 36 mounted on a suitable standard 37 secured to the ring 26 and then through a sheave 38 which is supported at the lower end of one of the primary cables C heretofore referred to. After passing said sheave 38 the cable C' extends downwardly and is secured to a dog 39 pivotally supported on one of the members 21, 21 of the upper arm section.

From this construction it is apparent that an upward pull upon the primary cable C connected to the sheave 38 will simultaneously withdraw the dogs 30 from the levers 25 and also lift the dog 39 out of contact with the part which it normally engages.

One of the primary cables C heretofore referred to is secured to each of the levers 25. These cables as heretofore noted pass upwardly through suitable guides and rollers and are secured to the operating paddles or levers 19 on the cage 10. Other secondary cables C², C³, C⁴ are also secured to the levers 25 these last named cables passing downwardly and being connected to certain movable parts of the arm hereafter described. It will thus be seen that when the levers 25 are drawn upwardly by the cables C, the cables C², C³, C⁴ will also be drawn upwardly to move the parts to which they are attached. When the levers are thus raised they will be locked in raised position until released by a pull upon the cable C' which withdraws the dog 30 and also the dog or dogs 39.

Near its lower end, the upper arm section 11 is provided with laterally extending bars 40 between which there is arranged a guide roller 41 and similarly laterally extending bars 42 are arranged a slight distance be-

low the ring 26 the bars 42 being connected by a cross bar 43 which if desired may carry suitable guiding rollers. The cross bar 43 and the guide roller 41 are intended to form 5 guiding means for one of the primary cables C which extends downwardly from the cage, and which is attached to the upper part of the lower arm section for swinging the same as later described. Other means are provided 10 for guiding the secondary cables which extend downwardly to the lower section of the arm, such means comprising a rod 44 carrying a tubular roller 44^a and arranged between bars 44^b, 44^c secured to the 15 members 21 of the upper arm section.

The lower arm section 12 is pivotally supported on the lower ends of the bars 21, 21 of the upper arm section, the lower arm section being provided with spaced bars or 20 members 45, 45, which are pivoted to said bars 21, 21, by pivot pins 46. One or both of the bars 45, 45 above its pivot point is provided with a curved portion 47 having a series of notches or teeth 48 so positioned 25 as to be engaged by the dog or dogs 39 heretofore described, it being understood that when the lower arm section is moved about its pivot 46, 46, the dog 39 cooperating with the teeth 48 will hold or lock such section 30 in the position to which it has been moved. The lower arm section may be moved about its pivot point through the medium of one of the primary cables C heretofore referred to, this cable extending from the cage downwardly to a point below the pivotal connection 35 between the upper and lower arm sections and being connected to a ring 50 which is rigidly secured to the bars or members 45 above mentioned. From this construction 40 it will be apparent that where this particular cable C is moved through the medium of the paddle or lever 19 to which it is secured the lower arm section will be caused to swing about its pivot 46, 46 relative to the 45 upper arm section.

The lower arm section is composed of two portions one of which is rotatable on a longitudinal axis, relative to the other portion. To secure such relative rotation there is 50 provided a ball bearing connection between such portions, this connection being formed by a ring 51 rigidly secured to the ring 50 and a second ring 52 which is secured to spaced members 53 forming the lower portion 55 of the lower arm section, suitable balls 54 being arranged between said rings 51 and 52.

To provide means for rotating the lower portion of the arm section 11 relative to the 60 upper portion, a drum 55 is rigidly secured to said lower portion of the section 11 this drum being arranged substantially axially of the said section, 11. The secondary cable C² above mentioned is attached to and 65 passes around the drum 55 and thence about

a guide roller 56, secured to the upper portion of the lower arm section, the cable C² at its end being secured to one of the levers 25 as above described. It is apparent that when said cable C² is drawn upwardly by 70 movement of the proper lever 25 the drum 55 and the lower portion of the arm section 11 secured thereto will be caused to rotate. A coiled spring 57 is secured at one end to the ring 52 and at the other end to the upper portion of said lower arm section which spring serves to return the rotatable portion of the arm section 11 to its original position when the same is free to rotate. The drum 55 is preferably secured to a tubular member 60 rigidly secured to the lower portion of the arm section 11, this member serving as a guide for the various secondary cables which pass downwardly to other movable parts of the arm. Between 75 the lower portion of the members 53 there is rigidly secured suitable rings 61, 62 which serve to hold said members 53 in rigid relation and also serve for the attachment of suitable covering for the arm. 80

The hand section 13 is pivotally supported on the lower ends of the members 53 above mentioned. The hand section comprises a cross member 65 pivotally connected at each end to the member 53 and provided with 85 ears 66 to which the frame member 67 of the hand is pivotally connected, this member 67 carrying cross bars 68, 69 rigidly secured thereto and upon which bars the finger members of the hand are supported. Each of the finger members is made up of two sets of parallel plates pivotally connected together. Referring to one of the finger members, all of which are similarly constructed, such member comprises two plates 70 mounted upon the bars 68, 69, and slidably engaged by a cross bar 71 upon which coiled springs 72 are arranged to space the different finger members. Each of the plates 70 is slotted longitudinally as at 90 73 and a cross bar 74 is arranged to slide in the slots of these plates. This cross bar is connected to the lower end of the secondary cable C³ so that as said cable is drawn upwardly the bar 74 will move in the slot 73. 105

The outer portion of each of the finger members is made up of sets of spaced plates 75 pivoted together and suitably held in spaced relation. A cord 76 passes from the bar 74 outwardly along each finger member there being suitable guides 77 in each of such members for holding said cords in proper position. These cords 77 are secured to the outer end of the finger members. Each of these members is also provided with a second cord 78 attached to its outer end, this cord extending rearwardly past suitable guides 79 and being secured to one end of a coiled spring 79^a, the other end of said spring being attached to the cross bar 68. 110

From this construction it will be seen that when the cable C^3 is drawn upwardly the jointed portions of the finger members will be bent and the fingers of the hand closed 5 and that when such jointed portions are free to move they will be restored to their original extended position by the springs 79^a acting through the cords 78 .

The thumb portion of the hand section, 10 comprises a member, 80 , which is pivotally supported on a plate 81 secured to the frame 67 and the outer jointed elements 82 similar to the jointed members 75 of the fingers. The secondary cable C^4 is connected to the 15 outer end of the jointed elements of the thumb member and is so arranged in this member that a pull upon said cable will cause bending of the thumb member toward the finger members of the hand section.

20 From the entire construction heretofore described, it will be understood that the lower arm section can be swung relative to the upper arm section, and locked in position and released when desired, and that one 25 portion of the lower arm section may be rotated relative to the other portion and locked in this position until released. And it will be further understood that the jointed finger and thumb members of the hand section may 30 be closed and released at will and that after the various parts have been moved as desired and locked, they may be simultaneously released from such locked position.

Various changes in the details of this 35 construction may of course be made without departing from the spirit of the invention or sacrificing any of the benefits or advantages thereof.

Having thus described the invention what 40 is claimed as new and desired to be secured by Letters Patent is:—

1. In an artificial arm, means for supporting the same on the body of a person, an upper arm section secured to said supporting means, a lower arm section pivotally secured to the lower end of the first named section, one of said arm sections having adjacent its point of pivotal support a portion provided with a series of notches, a dog 45 movably mounted on the other section and arranged to engage said notches as the lower arm section is moved relative to the upper section, means for moving said lower arm section relative to the upper arm section 50 and means carried by the upper arm section 55 for withdrawing said dog from said notches.

2. In an artificial arm, a cage, an upper arm section secured thereto, a lower arm section pivotally secured to the lower end of the first named section, one of said arm sections having adjacent its point of pivotal support a portion provided with a series of notches, a dog movably mounted on the other arm section and arranged to engage 60 said notches as the lower arm section is

65 moved relative to the upper arm section, means operable from the cage for moving said lower arm section relative to the upper arm section and means also operable from the cage for withdrawing said dog from said notches. 70

3. In an artificial arm, a cage adapted to be secured to the shoulder of a person, an upper arm section pivotally secured thereto, a lower arm section pivotally connected to the lower end of the upper section, said lower arm section having at its upper end a curved portion provided with a series of notches, a dog movably mounted on said upper section and arranged to engage said notches as the lower section moves about its pivotal connection, means operable from the cage for moving said lower arm section relative to the upper arm section, and means also operable from the cage for withdrawing said dog from said notches. 80

4. In an artificial arm, an upper arm section, a lower arm section pivotally connected thereto, means arranged adjacent the pivotal connection between said sections for locking the lower arm section against movement relative to the upper arm section, a cable for releasing said locking means and a movable device mounted on said upper arm section to which said cable is connected. 90

5. In an artificial arm, a cage adapted to be secured to the shoulder of a person, an upper arm section connected to said cage, a lower arm section pivotally connected to said upper arm section, means adjacent the pivotal connection between said arm sections for locking said lower arm section against movement relative to the upper arm section, means operable directly from the cage for moving said lower arm section 100 about its pivotal connection to the upper arm section, a cable for releasing said locking means, a movable device mounted on said upper arm section to which said cable is connected and means operable from the cage for moving said device. 105

6. In an artificial arm, an upper arm section and a hand section, a lower arm section connected together, said lower arm section above the hand section consisting of two 110 portions, means for rotating one portion of said lower arm section relative to the other portion, means for locking said rotatable portion in various positions, and means for releasing said locking means. 115

7. In an artificial arm, a cage, an upper arm section and a lower arm section pivotally connected, a hand section connected to said lower arm section, said lower arm section comprising two portions one of which 120 is rotatable relative to the other on a longitudinal axis, means for rotating said rotatable portion of the lower arm section and means for returning the same to its original 125 position. 130

8. In an artificial arm, an upper arm section, a lower arm section pivotally connected thereto, means for moving the last named section about its pivotal connection with the upper arm section and means for locking the same in various positions, said lower arm section comprising two portions one of which is rotatable relative to the other, means for rotating said rotatable portion, means for locking the same in various positions, and means for simultaneously releasing each of said aforementioned locking means.
9. In an artificial arm, an upper arm section, a lower arm section pivotally connected thereto, a hand section connected to the lower end of said lower arm section said lower arm section comprising two portions, one of which is rotatable relative to the other on a longitudinal axis, means mounted on the upper arm section for rotating said rotatable portion of the lower arm section, means for locking said rotatable portion in various positions and means for releasing said locking means.
10. In an artificial arm, an upper arm section, a lower arm section and a hand section connected together, said lower arm section comprising two parts, one of which is rotatable on a longitudinal axis relative to the other part, a cable connected to said rotatable part of the lower arm for rotating the same, means to which said cable is connected for locking said rotatable part in various positions, a cable for releasing said locking means and movable means carried by the upper arm section to which said last named cable is connected.
11. In an artificial arm, an upper arm section, a lower arm section secured thereto, a hand section secured to said lower arm section, said hand section comprising a series of jointed members representing fingers, means for yieldingly holding said jointed members extended, means for simultaneously bending said jointed members to close the hand, means for locking said jointed members in their bent position, and means for releasing said locking means.
12. In an artificial arm, an upper arm section, a lower arm section secured thereto, a hand section secured to said lower arm section, said hand section comprising a series of jointed members representing the thumb and fingers of the hand, means for yieldingly holding said jointed members extended, means for simultaneously bending said jointed members constituting the fingers, other means for bending said jointed member constituting the thumb of the hand, means for locking each of said jointed members in bent or contracted position, and means for simultaneously releasing said locking means.
13. In an artificial arm, a cage, an upper arm section, a lower arm section, a hand section, said hand section comprising a series of jointed members representing fingers, means for yieldingly holding said jointed members extended, means operable from the cage for simultaneously bending said jointed members to close the hand, means for locking said jointed members in their bent position, and means operable from the cage for releasing said locking means.
14. In an artificial arm, a cage adapted to be mounted on the shoulder of a person, an upper arm secured to said cage, a lower arm section pivotally secured to said upper section, means operable from the cage for moving said lower arm section about its pivot, means for locking the same in various positions, said lower arm section comprising two portions one of which is rotatable relative to the other, means operable from the cage for rotating said rotatable portion, said means including a locking device for holding said rotatable portion in desired position of rotation, and means operable from the cage for simultaneously releasing said locking means and said locking device.
15. In an artificial arm, a cage for attachment to the shoulder of a person, an upper arm section secured to said cage, a lower arm section pivotally secured to said upper section, a hand section secured to said lower arm section, means operable from the cage for moving said lower arm section about its pivot, a device for locking the same in various positions, said lower arm section comprising two portions one of which is rotatable relative to the other, means operable from the cage for rotating said rotatable portion, said means including a locking device mounted on said upper arm section for holding said rotatable portion in desired position, said hand section comprising a plurality of jointed members, means operable from the cage for bending said members to close the hand, said means including a locking device on said upper arm section for holding said jointed members in bent position, and means operable from the cage for simultaneously releasing each of said locking devices.
16. In an artificial arm, a cage adapted for attachment to the shoulder of a person, an upper arm section secured to the cage, a lower arm section secured to said upper section, said lower section comprising two portions one of which is rotatable relative to the other, a hand section secured to said lower arm section and comprising a series of jointed members constituting the fingers of the hand section, a lever pivotally mounted transversely of said upper arm section and provided with a plurality of notches, a dog also pivotally mounted on said upper arm section and arranged to engage the notches of said lever, a cable connected to

1. In an artificial arm, a cage adapted to be secured to the shoulder of a person, a member pivotally supported on said cage and capable of movement about a predetermined axis, an upper arm section pivotally supported on said member and capable of swinging movement about an axis substantially at right angles to the first mentioned axis, means for locking said arm section against swinging movement relative to said member, and means operable from the cage for releasing said locking means.
2. In an artificial arm, a cage adapted to be secured to the shoulder of a person, said cage having a curved member adapted to extend over the shoulder of a person and also having a top member secured to and extending laterally of said first named member and substantially at a right angle thereto, an arm pivotally secured to the outer end of said top member, said arm including a
3. In an artificial arm, a cage adapted to be secured to the shoulder of a person, an upper arm section secured to the cage, a plurality of levers pivotally supported transversely of said section each provided adjacent its free end with a plurality of notches, a dog pivotally mounted adjacent the free end of each of said levers and arranged to engage said notches, a plurality of movable parts supported by said upper arm section, a cable connected to each of said levers and to one of said movable parts, means operable from said cage to move said levers and the parts attached thereto, and means also operable from said cage for withdrawing said dogs from said notches.
4. In an artificial arm, a cage, an arm section secured thereto, a hand section secured to said arm section, said hand section comprising a plurality of jointed members constituting the fingers, yielding means for holding said jointed members extended, means operable from the cage for bending said jointed members to close the hand, means mounted on the arm section for locking said jointed members in bent position, and means operable from the cage for releasing said locking means.
5. In an artificial arm, a cage adapted to be secured to the shoulder of a person, an upper arm section pivotally supported from said cage and arranged to swing about an axis, means for locking said arm section against swinging movement about said axis and relative to the cage, and means operable from the cage for releasing said locking means.
6. In an artificial arm, a cage adapted to be secured to the shoulder of a person, a member pivotally supported on said cage and capable of movement about a predetermined axis, an upper arm section pivotally supported on said member and capable of swinging movement about an axis substantially at right angles to the first mentioned axis, means for locking said arm section against swinging movement relative to said member, and means operable from the cage for releasing said locking means.
7. In an artificial arm, a cage adapted to be secured to the shoulder of a person, said cage having a curved member adapted to extend over the shoulder of a person and also having a top member secured to and extending laterally of said first named member and substantially at a right angle thereto, an arm pivotally secured to the outer end of said top member, said arm including a

plurality of movable parts, a plurality of levers pivotally mounted on said cage, and cables connected to said levers and said movable parts for moving the latter.

8. In an artificial arm, an upper arm section, a plurality of levers pivotally supported at one end on said section and arranged in substantially parallel relation, each of said levers at its free end having an arm or projection provided with teeth, a plurality of spring pressed dogs pivotally supported adjacent said free ends of said levers and arranged to engage the teeth thereon, a plurality of movable parts supported from said upper arm section, cables connecting certain of said parts with said levers, means for moving said levers to operate the movable parts connected thereto and means for simultaneously releasing said dogs from said levers.

9. In an artificial arm, a section composed of two portions, means for maintaining said portions with their longitudinal axes in alignment, one of said portions being rotatable on a longitudinal axis relative to the other portion, means for rotating said rotatable portion and means for automatically returning the same to its original position.

10. In an artificial arm, a cage adapted to be secured to the body of a person, an upper arm section supported on said cage, a lower arm section pivotally connected to the upper arm section and capable of swinging on a predetermined axis only, means for moving said lower section about its pivotal axis, means for locking the same in the position desired, said lower section comprising two portions one of which is rotatable relative to the other, means for rotating said rotatable portion and for locking the same in desired position, a hand section secured to said lower arm section, said hand section comprising a plurality of jointed members normally held in extended position, means for bending said jointed members and locking the same in their bent position, and means operable from the cage for simultaneously releasing each of said locking means.

11. In an artificial arm having a plurality of relatively movable parts, a series of levers pivotally supported on one of said parts, a cable connected to each of said levers and to one of the parts to be moved, an operating cable connected to each of said levers for moving the same, and means for locking each of said levers in various positions when moved by said operating cables.

12. In an artificial arm having a plurality of relatively movable parts, a series of levers pivotally supported on one of said parts, a cable connected to each of said levers and to one of the parts to be moved, an operating cable connected to each of said levers for moving the same, a locking dog for each of

said levers to lock the same in various positions when moved by said operating cables, and means for simultaneously releasing said dogs from the levers.

5. 27. In an artificial arm having a plurality of relatively movable parts, a plurality of levers pivotally supported on one of said parts, each of said levers having a toothed arm secured thereto, a pivoted dog
10 for each of said levers, said dogs being arranged to engage the teeth of said levers and

hold the same in various positions, a cable connected to each of said levers and to one of the parts of the arm to be moved, an operating cable connected to each of said 10 levers for moving the same to various positions, and means for simultaneously releasing said dogs from the toothed portions of said levers.

In testimony whereof I affix my signature.

ROMAINE R. HARRIS.
